UNITED STATES PATENT OFFICE.

JOHN F. SMITH, OF TAUNTON, MASSACHUSETTS

SAFETY SHOE.

Application filed September 18, 1922. Serial No. 588,812.

To all whom it may concern:

Be it known that I, JOHN F. SMITH, a citizen of the United States, and a resident of Taunton, in the county of Bristol and 5 State of Massachusetts, have invented an Improvement in Safety Shoes, of which the following description, in connection with the accompanying drawings, is a specification, like characters on the drawings representing 10 like parts.

My invention relates to shoes and particularly to a protective shoe adapted to be worn by molders and others. One illustrative embodiment of my invention is disclosed 15 in the accompanying drawing wherein—

Fig. 1 is a side elevation of the right shoe of a pair, with the parts in position as worn;

Fig. 2 is an elevation of the opposite side of the same shoe with the parts in open 20 position; and

Fig. 3 is a section upon the line 3—3 of Fig. 1 looking in the direction of the arrows.

It has been customary heretofore so far as I am aware for molders and others engaged in handling molten metal to employ as 25 an outer foot-covering a half-boot or ankle-boot having a permanently closed front, and which is drawn onto the foot in the ordinary manner of a boot. With such a boot, which 30 for protective purposes must be of heavy leather, it is impossible to secure a snug fit of the upper about the ankle of the wearer, since said ankle portion of the upper must be sufficiently large in diameter to permit 35 the foot to be inserted into the boot and readily to be removed therefrom. This is true even where such expedients are resorted to as slightly elastic inserts in the side of the 40 boot upper. Also the boot must be of a somewhat larger size over all than is necessary with a laced boot or shoe. A laced shoe, however, cannot be worn by those engaged in the handling of molten metals for the reason that drops of the molten metal may readily 45 enter the shoe at the instep quickly burning through the lacings and tongue and injuring the foot of the wearer. Moreover, it is essential in this connection that the boot or shoe should be quickly removable by 50 the wearer in case any of the molten metal is spilled upon the foot which ability to be quickly removed is lacking in a laced shoe. My invention contemplates combining all 55 the advantages of a laced shoe which may be of the proper size to fit the foot and of the readily removable boot.

Referring more particularly to the drawings, the boot or shoe is indicated as a whole at 1 and comprises the upper 2 secured to an outsole 3 in a suitable manner. For the 60 purposes of illustration I have disclosed my invention in connection with a shoe of the welt type. Obviously, however, my improved protective upper may be employed in connection with any desired type of sole. 65 As seen most clearly in Fig. 3 the upper 2 is secured to an insole 4 and to the usual welt 5 to which in turn is secured said outsole 3.

The upper 2 is open at the front or instep 6, at which point the boot may be provided with the usual tongue not shown, preferably secured at both edges to the inside of the upper and of relatively thin flexible material sufficiently full to permit the foot readily to be inserted into the shoe. Said opening 70 preferably and as shown herein extends from the top of the upper to a point forward of the ball line.

Along one side of the front portion 6 of the upper 2 and preferably the side at the 80 inside of the foot of the wearer is formed a broad flap-like member or extension 7 of sufficient size and extent to be folded down and across the instep and to extend well down upon the opposite side of the shoe. 85 Said flap 7 preferably extends from a point adjacent the toe portion to the top of the upper 2, and as is clearly apparent in the drawings extends forwardly of the ball line 90 of the shoe. As herein shown, said flap 7 is 95 secured to the front portion 6 of the shoe upper 2 by the line of stitching 8. If desired, however, said flap portion 7 may be formed integrally with the shoe upper.

Any suitable means may be provided for 95 removably holding the flap 7 in closed position, such as snaps or the like provided only that said means be of a quickly releasable type. Herein for the purpose I have disclosed a series of fasteners 9 positioned 100 along the outer edge of the flap 7 and adapted to cooperate with a similar number of studs 10 secured along the upper 2 upon the outer or right side of the right shoe as worn. The fasteners for the left shoe of the pair, 105 not necessary to be shown, are preferably also upon the outer or left side of said shoe, thus avoiding any possibility of interference between the shoes. Any suitable number of fasteners may be employed and herein I have 110 shown three fasteners and three cooperating studs.

From the above description it will readily be understood that the boot or shoe herein disclosed may be formed to fit snugly about the ankle of the wearer, leaving no gap at the top of the shoe as in the case of the usual boot now worn which provides a ready entrance for molten metal and the like. The flap-like member 7 is of sufficient breadth and length fully to cover the instep portion, giving the wearer complete protection and rendering the boot practically proof against the entrance of molten metal or other extraneous matter.

Heretofore, with the boot ordinarily worn, a molder who had received a burn might be incapacitated for the performance of his work for a period of weeks until the injury had completely healed, since in attempting to draw on the customary boot over the incompletely healed burn, the newly forming tissue would invariably be injured, greatly delaying the proper healing of the wound. To avoid such further injury, a molder would frequently resort to cutting open the boot thereby lessening greatly its protective value. The shoe as herein disclosed, however, may be put on comfortably and the flap folded down and fastened without damage to an incompletely healed burn even upon the instep of the wearer, the portion of the foot most frequently injured. At the same time I have provided a shoe which is practically instantaneously removable in the case of emergency, it being necessary only to grasp and pull up the edge of the flap, whereupon the shoe may be pulled or kicked off from the foot of the wearer.

While my shoe is particularly adapted for wear by molders and others engaged in handling molten metals, obviously it is not limited to such use but is serviceable in any connection requiring a protective or waterproof shoe.

Having thus described my invention I desire it to be understood that I am not limited to the particular illustrative embodiment disclosed, the scope of the invention being set forth in the following claims.

Claims—

1. A shoe having an upper formed with a through opening at the front thereof and a flap-like extension along one edge of said open front from a point adjacent the toe to the top of the upper and adapted to be folded across the instep and well down upon the opposite side of the shoe upper thereby

to provide a relatively broad deeply-overlapping protective covering for the opening in the upper.

2. A protective shoe for molders having an upper open at the front thereof from the top to a point in the toe, a flap along one edge of said open front, and cooperating fastening means upon said flap and upon said upper whereby said flap may be securely held in closed position but may be instantly released to free the foot of the wearer of the shoe.

3. A protective shoe for molders having an upper provided with a through opening at the front thereof from the top to a point adjacent the toe and a broad flap-like extension along the entire length of one edge of said opening, said flap-like extension having a width at its lowermost portion at least equal to approximately one half its greatest width, a series of fasteners adjacent the free edge of said extension and cooperating means mounted directly upon the shoe upper well down on the side thereof opposite to that carrying said flap-like extension thereby releasably to secure said extension in deeply-overlapping closed position.

4. A protective shoe having an upper provided with an opening from the top to a point forward of the ball line, a broad flap-like extension along the entire length of one edge of said opening, a series of fasteners adjacent the free edge of said extension and cooperating means upon the shoe upper releasably to secure said extension in closed position across said opening.

5. A protective shoe having an upper provided with an opening from the top to a point forward of the ball line, a flap upon the upper along one side of said opening and quick-releasable fastening means for securing said flap in closed position across said opening.

6. A protective shoe having an upper provided with a substantially central opening at the front thereof extending from the top of said upper to a point beyond the ball line of the shoe, a flap fixed upon the upper at one side thereof and having a series of fasteners adjacent its free edge and cooperating means upon the opposite side of the upper thereby to secure said flap in closed position across said opening.

In testimony whereof, I have signed my name to this specification.

JOHN F. SMITH.
